(57) **CLAIM**

An ornamental design for a display screen or a portion thereof with a graphical user interface, as shown and described.

DESCRIPTION

The FIGURE is a front view of a display screen or a portion thereof with a graphical user interface showing the new design.

The outer broken lines in the FIGURE show a display screen or a portion thereof that forms no part of the claimed design. The inner broken lines in the FIGURE show portions of the graphical user interface that form no part of the claimed design.

UNITED STATES PATENT AND TRADEMARK OFFICE
CERTIFICATE OF CORRECTION

PATENT NO. : D809,555 S
APPLICATION NO. : 29/593708
DATED : February 6, 2018
INVENTOR(S) : Navin Prasad, Paul Anastasopoulos and Cameron Johnson

Page 1 of 1

It is certified that error appears in the above-identified patent and that said Letters Patent is hereby corrected as shown below:

On the Title Page

Item (54) and in the Specification, Column 1, Line 1-2:

Please delete “DISPLAY SCREEN OR PORTION THEREOF WITH A GRAPHICAL USER INTERFACE” and insert --DISPLAY SCREEN OR PORTION THEREOF WITH GRAPHICAL USER INTERFACE--.

Signed and Sealed this
